U.S. Cl. D54—1

FIG.1

FIG.2

FIG.3

FIG.6

FIG.4

FIG.5

FIG.7

FIGURE 1 is a perspective view of a combined control motor housing and mounting bracket therefor embodying our new design;

FIGURE 2 is a front view thereof;

FIGURE 3 is a side view thereof, as viewed from the right of FIGURE 2;

FIGURE 4 is a side view thereof, as viewed from the left of FIGURE 2;

FIGURE 5 is a rear view thereof;

FIGURE 6 is a top plan view thereof; and

FIGURE 7 is a bottom plan view thereof.

The dominant features of our design reside in the portions shown in full lines.

We claim:

The ornamental design for a combined control motor housing and mounting bracket therefor, as shown and described.
